The ornamental design for an electronic cigarette mouthpiece as shown and described.

DESCRIPTION

FIG. 1 is a perspective view of an electronic cigarette mouthpiece showing my new design;

FIG. 2 is a front side elevational view of the electronic cigarette mouthpiece of FIG. 1;

FIG. 3 is a rear side elevational view of the electronic cigarette mouthpiece of FIG. 1;

FIG. 4 is a left side elevational view of the electronic cigarette mouthpiece of FIG. 1;

FIG. 5 is a right side elevational view of the electronic cigarette mouthpiece of FIG. 1;

FIG. 6 is a top plan view of the electronic cigarette mouthpiece of FIG. 1; and,

FIG. 7 is a bottom plan view of the electronic cigarette mouthpiece of FIG. 1.

The broken lines formed by even length segments depict portions of the electronic cigarette mouthpiece that form no part of the claimed design. The broken lines formed by dash-dot-dash segments define a boundary of the claimed design and form no part thereof.
